UNITED STATES PATENT OFFICE.

ZDENKO PODHRADSKY, OF ASTORIA, NEW YORK, ASSIGNOR TO H. R. MALLINSON & CO., INC., OF NEW YORK, N. Y., A CORPORATION OF DELAWARE.

JACQUARD ATTACHMENT FOR LOOMS.

Application filed December 21, 1923. Serial No. 681,904.

To all whom it may concern:

Be it known that I, ZDENKO PODHRADSKY, a citizen of Czechoslovakia, and resident of Astoria, borough and county of Queens, city 5 and State of New York, have invented certain new and useful Improvements in Jacquard Attachments for Looms, of which the following is a specification.

My invention relates to looms and more particularly to that type of looms which include a jacquard attachment. The latter generally consists of a series of perforated cards connected together by flexible means such as cords or the like and mounted upon 10 wires whereby said cards are supported in the loom. Heretofore the wires have been attached in position in various ways, all more or less unsatisfactory and including undesirable features. The object of the present invention is to provide a novel arrangement and construction which enables the supporting wires to be attached to and detached from the cards, at will, in a simple manner and without requiring any special 15 skill in the performance of the operations. Other more specific objects will appear from the description hereinafter.

In the accompanying drawing, which illustrates an example of the invention without defining its limits, Fig. 1 is a face view of a series of jacquard cards with the improvement applied thereto; Fig. 2 is a sectional view on the line 2—2 of Fig. 1; Fig. 3 is a fragmentary plan view of one of the 20 supporting wires with the novel connecting means combined therewith, showing the same in connection with the jacquard cards, and Fig. 4 is a fragmentary side view of one of said wires.

As shown, the jacquard attachment comprises a plurality of cards 10 located adjacent to each other and provided with the customary perforations 11, said cards being 25 flexibly connected with each other by means of cords 12 or the like in the well known way. As shown in Fig. 1 the cords 12 are threaded through suitable openings at opposite ends of the cards and at the centers thereof, so that said cords extend along opposite edges of the series of cards and along 30 the median line thereof in the customary manner.

The supporting wires 13 are located between adjacent cards 10 as shown in Fig. 1 35 and extend beyond the opposite ends there-

of to form projections whereby said cards are supported in the loom in the customary manner. At those points which are in registry with the cords 12, the wires 13 are bent or otherwise constructed, to provide seats 14 60 in which the cords 12 are located. The means whereby said wires are detachably connected with the cords comprise resilient fingers 15 which are secured at one end to the wires, preferably in close proximity to the seats 14 thereof, and which extend lengthwise of said wires over and beyond said seats as shown in Fig. 3; the free end of the resilient fingers preferably extends in directions away from the wires as indicated at 16. As shown in the illustrated example, the resilient fingers may consist of 65 relatively fine wires which have one end coiled about the wires 13 so as to be affixed in position thereon, said coiled ends being 70 soldered to the wires 13 if desired to prevent any shifting of the fingers 15. As shown in the drawings and more particularly in Fig. 3, the fingers 15 all extend in the same direction lengthwise of the wires 13 with the 75 inclined ends 16 thereof forming inner angles with the wires 13, which angles all open in the same direction.

With the described arrangement, the wires are easily connected with the cords 12 by 80 simply introducing each wire in the space between the adjacent cards and with the cords lying in the angles formed by the inclined ends 16, after which a push in the direction of the length of the wire 13 is exerted 85 thereon to force said fingers 15 over the cords 12 and to bring the latter into the seats 14. In this position the resiliency of the fingers 15 locks the cords 12 in the seats 14 90 and prevents any movement of the wires 13 95 relatively to said cords. When it is desired to detach the wires, a push or pull in the relative direction is exerted thereon, whereby the cords 12 are withdrawn from the seats 14 and from beneath the fingers 15; the 100 inherent resiliency of the latter causes said fingers to yield sufficiently to permit this disconnection of the wires 13 in a simple and efficient manner, without any particular 105 manual effort.

The invention is extremely simple and reduces the operation of connecting and disconnecting the wires to the simplest form. At the same time the necessity for tying the 110 wires 13 in position for flexing or bend-

ing the cards to enable the wires to be placed in or removed from operative position is entirely done away with.

Various changes in the specific form shown and described may be made within the scope of the claims without departing from the spirit of my invention.

I claim:

1. In a jacquard attachment for looms, 10 the combination of a plurality of perforated cards, flexible connections tying said cards together, a supporting wire extending lengthwise between adjacent cards and resilient clamping means facing in the same direction for detachably connecting said wire with said flexible connection.
2. In a jacquard attachment for looms, 20 the combination of a plurality of perforated cards, cords tying said cards together, a supporting wire extending between adjacent cards and resilient fingers extending lengthwise of the wire and having their free ends pointing in the same direction for detachably connecting the wire with said cords.
3. In a jacquard attachment for looms, 25

the combination of a plurality of perforated cards, cords connecting said cards together and extending along opposite edges and centrally thereof and a wire extending between adjacent cards and provided with seats in registry with said cords for the accommodation thereof, and a plurality of resilient fingers extending lengthwise of said wire over said seats and having their free ends projecting in the same direction whereby 35 said cords are maintained in said seats and said wire is detachably connected with said cords.

4. In a jacquard attachment for looms, 40 the combination of a supporting wire provided at spaced intervals with seats, resilient fingers having one end fixed to said wire in close proximity to said seats, said fingers projecting across said seats and having their other ends disconnected from said wire and 45 pointing in the same direction to form pockets opening in said direction.

In testimony whereof I have hereunto set my hand.

ZDENKO PODHRADSKY.
